[57] CLAIM

The ornamental design for a hearing aid transducer or the like, as shown and described.

DESCRIPTION

FIG. 1 is a front and bottom perspective view of a hearing aid transducer or the like showing my new design;

FIG. 2 is a left side elevational view with an electrical ear plug connection and an ear insert shown in broken lines for illustrative purposes only and forming no part of the claimed design; and

FIG. 3 is a top plan view.
